(57) **CLAIM**

I claim the ornamental design for a cup, as shown and described.

DESCRIPTION

FIG. 1 is an upright, perspective view of the first embodiment of a cup, showing my design.

FIG. 2 is an inverted, perspective view of the first embodiment of a cup, showing my design.

FIG. 3 is an enlarged view of a bottom portion of the first embodiment of a cup, showing my design.

FIG. 4 is a perspective view of the first embodiment of a cup, showing my design.

FIG. 5 is a perspective view of the second embodiment of a cup, showing my design.

FIG. 6 is a perspective view of the third embodiment of a cup, showing my design.

FIG. 7 is a perspective view of the fourth embodiment of a cup, showing my design.

FIG. 8 is a perspective view of the fifth embodiment of a cup, showing my design; and,

FIG. 9 is a perspective view of the sixth embodiment of a cup, showing my design.

1 Claim, 3 Drawing Sheets
